John L. St. John of Canajoharie New York.

Letter Patent

The Schedule referred to in this Letter Patent and making part of the same, containing a description in the words of the said John L. St. John himself of his improvement in reaction water wheels.

To all to whom these presents shall come. Be it known that I, John L. St. John, of Canajoharie, in the County of Montgomery and State of New York have invented a new and useful improvement in Reaction Water wheels, and wheels, operating by the power of reaction.

I. By the invention of a new form or forms of wheels. It being apparent on those already in use - and that the following is, a full and exact description of the construction and operation of the said wheels and improvements as invented and improved by me.

I. The description of the construction and operation of the new form or forms of the wheels and the variations.

These wheels have openings, at or near the edge, ^{and} through which the water passes. and it is the passing of the water through these openings that creates the power of reaction by which the wheels operate.

These openings or spouts give direction to the water, at or near a right angle with the radii of the wheel drawn through them and with as little angle to the face of the wheel as possible. The number and form of these openings in a wheel is not material. The diameter of a wheel with the quantity of water discharged through it must vary to suit the fall of water and the power and the velocity required. The thickness of these wheels must be sufficient to form the spouts, and be varied accordingly. although the diameter and thickness of these wheels, and the number and size of their spouts must be varied, yet to explain the construction. I will describe the forming of one of 32. inches in diameter, 3 inches thick with 6 spouts discharging 100 square inches of water. This is easily done by taking as many pieces of 3 inch

blocks and cut them so that each piece will form an equal part of the rive of the wheel with a point in the centre. Then describe on this wheel a ^{two} ~~inner~~ circle, the circumference being the largest 225 inches in diameter, the other 20 inches in diameter. Then take each piece and cut down on the opposite corners, between the circles, deep enough so that when the pieces are placed together, an opening will be formed 2 $\frac{1}{2}$ inches deep cut back between the circles so that the timber left will be only about $\frac{1}{8}$ of an inch thick. This timber left may be called the bucket, and the timber between them and the rive, the rim, and the timber between the buckets, the head. This wheel must then be banded or fastened together, and an opening made in the centre, to receive the shaft or The pieces may be fitted into a groove turned or cut into the shaft and then banded. The inner corner of the head should be rounded off so that the water can come to the place of issue freely. Also the corners of the head and rim on the outside of the wheel should be rounded or sanded off, so that the water may be discharged freely.

The ends of the buckets, or timber left between the buckets, may be taken off, so that a line drawn at right angles with the direction of the water from the end of one of the buckets, across the rive, will be direct to the end of the other. The rim or timber at the rive may all be taken off down to the buckets, or the wheel may be made without a rim, or a wheel may be made in this form by fast making the head and then placing the buckets on the rive of it, then turning out the outer edge of them after the wheel is hung on the shaft.

These wheels, which have no rim must have a cylinder top or rim placed around them, and as near to the outer edge of the buckets as it can be without touching them. These wheels, may be made of cast iron by having a plate cast to suit in form, one side of the wheel. In some situations, wheels will do best if they are so constructed that the water discharges ^{up} through the edge that is, so that when the wheel is placed on an upright shaft the water discharges horizontally. To form one, make a head of 18 inches in diameter, then describe a circle of 22.5 inches on it. Then draw as many radiating lines from

the centre to the edge with equal distances, as you want issues. Then draw a curving line from each radiating line at the top to another at the circle. Then cut off the head down to the curving lines. Then fasten the buckets on the curving lines which may be made of cast iron, or sheet iron and do that they will project about $5\frac{1}{2}$ inches above the head, have them long enough to reach from one radiating line to another, these form a rim 32 inches in diameter, $1\frac{1}{2}$ inch thick. Then cut the inner edge to suit the form and size of the outside of the buckets. Then fasten these rim on the buckets so that the top of the rim will be even with the top of the buckets. The form and size of these may be varied. This wheel should be filled up in the centre around the shaft level with the rim and slanted off down to an edge, at the inner end of the buckets. If a spout is used, the filling up should be carried out level far enough for the spout to be fitted against. Then wheel, ^{also} may be made of cast iron, by having a plate cast to suit the form of the inward and face side of the wheel, with or without the filling, up around the shaft. Wheels, may be made different from any of the forms, above described, by having the water discharged partly at the side and partly at the edge, and the form of the issues, may be varied they may be round, elliptical, oblong, or square, or the inner face corner may be rounded and the outward back corner also. The form of the sides, &c, not material of a proper quantity is discharged, the size of the issues may be made so as to lap by each other, but if they do the motion and power will be diminished in proportion to the distance of the lapping — II. The improvements of those already in use:

First, this improvement consists in using less lapping by of the ends of the buckets. Then has been heretofore used.

Second in having less lapping by the sides of the issues than has been heretofore used. Third in making rattling the wheel, so that the water will not be stopped by the wheel neither before it comes to the place of issue, nor after it passes it, and only at a single line in the face.

Fourth, in so forming and attorney the wheel that the water can come to the issue, free and direct and pass through it without friction.

Sept 10, 1834

and be discharged without obstruction. The common reaction water-wheels now in use, have a head or main part which is, fixed to the shaft, on this head the buckets, so called are placed and covered with a rim. The water passes, through this rim, into the wheel, and between the buckets, out of the wheel. The ends, of the buckets, lap by each other, more or less. These wheels, may be improved in the following way. First, by cutting off the inner or head ends, of the buckets. Second, by cutting off the inner edge of the rim. Third, by cutting off the outer edge of the head. Fourth, by filling up the hub in the centre. Each of these I consider as separate improvements, and are done in the following manner. — First, to cut off the buckets, draw converging lines, from the point or outer end of each bucket to the centre of the wheel, then cut off the head or inner ends, of the buckets, so that they shall not pass these lines, and so that the sum of all their lengths, will not be quite equal to the circumference of the wheel. Second to cut off the rim, cut off all that projects, in beyond the inside, of the buckets, even with the buckets, ^{in form with the buckets} and at the place of issue follow the converging line from one bucket to the other, and then if the rim is not sufficient in width, add to it in the cut edge, an additional rim can be fixed on it so that the inner edge will be even with the points, of the buckets, and turned off true on the inner edge for the spool cylinder or flaring to be fitted against. Third, to cut off the head, cut off all that projects, beyond the outside of the buckets, back to fill up the wheel in the centre take blocks, and fit them round the shaft, and even with the top of the rim, and planing off, down to an edge at the inner ends, of the buckets. This filling up may be carried out level far enough for the inner edge of a spout to be fitted against when it is used.

The advantages of the several improvements are. First, the cutting off of the buckets, allow the water to pass the rim without friction. Second, the cutting off of the rim, allows the water to come direct and free to the spout. Third, the cutting off of the heads, allows the water to escape without obstruction, Fourth,

Sept 10, 1834

In filling up of the wheel presents any water lying dead in the wheel and directs the water to the iface and fans it surface for the front to be filled against. Some wheels are so formed that one edge of the buckets is placed towards the centre of the wheel, and so that when a wheel is placed on a perpendicular shaft, the water will be discharged upward or downward. To improve these wheels, draw a line from the front or outer end of each bucket parallel with the shaft. Then cut off all the heads or inner ends of the buckets, so that they shall not pass any of these lines. Then cut off all the tubs or iron that project below or beyond the outside of the buckets, and no form to suit the buckets. This allows the water to pass the iface without friction, and be discharged freely. All other forms of wheels may be improved by altering them agreeable to the above principles and Rules, explained. All the above forms of wheels, whether new or improved, may be used in any way, manner or situation that wheels operating by the power of reaction are now used.

The parts of the above described wheels and improvements, claimed original and as my invention, and for which I ask an exclusive privilege are. I. The new forms of wheels as described in the first part. II. The improvements, as explained, and the various improvements as described in the second part.
